UNITED STATES PATENT OFFICE.

ROLAND R. CRUM, OF WHITTIER, CALIFORNIA, ASSIGNOR, BY DIRECT AND MESNE ASSIGNMENTS, TO L & B PRODUCING & DRILLING CO., A CORPORATION.

PUMP.

Application filed August 18, 1923. Serial No. 658,054.

To all whom it may concern:

Be it known that I, ROLAND R. CRUM, a citizen of the United States, residing at Whittier, in the county of Los Angeles, State of California, have invented a new and useful Pump, of which the following is a specification.

My invention relates to pumps, and while it may be applied to pumps used for many purposes, it is peculiarly applicable to oil well pumps. In the pumping of oil wells, it is standard practice to suspend a pump barrel at the lower end of a string of tubing which extends down into the well. A plunger is reciprocated in the pump barrel by a wire rope, or preferably by sucker rods, the wire rope or sucker rods being connected to suitable means on the surface of the ground for reciprocating the same. In the case of widely scattered or deep wells, a motor or engine is ordinarily provided at the well, this motor or engine being usually situated outside the derrick and operating the wire rope or sucker rods through suitable mechanism. The cost of maintaining individual engines or motors at the different wells is considerable, and the cost of distributing power to these different prime movers is also considerable. In cases where the power to be used at each well is small, as for example in shallow wells, or in old fields where the production is small, it is common practice to pump a number of wells from a single prime mover, which is located at some central point, and from which power is carried to the wells through wire ropes extending to the different wells above the surface of the ground and parallel thereto. This system is termed pumping by jacks and is in quite general use, saving large quantities of power.

It is an object of my invention to provide means by which a plurality of wells may be pumped from a central point without the necessity for any moving mechanism between the power plant and the well. The use of wire rope in actuating pump barrels is extremely limited and practically all wells are now pumped through sucker rods. In the case of all wells except very shallow

ones, the sucker rods are formed of steel rods having threaded connections. These rods are expensive and since they are reciprocated continuously inside the tubing, there is considerable wear thereon, so that the cost of up-keep is considerable. In deep wells, considerable trouble is experienced with rod breakage and any such breakage is expensive since it involves a shut down of the well and a more or less protracted "fishing job."

It is a further object of my invention to provide means for actuating the pump in a well without the use of sucker rods, wire lines, or other mechanical connections between the pump plunger and the surface of the ground. These objects I accomplish by the use of fluid under pressure as the actuating medium. This fluid under pressure may be compressed air or gas, or it may be oil of the same general character as that produced by the well. The term "fluid" as used hereinafter should be understood to include all gases and liquids. In the description we will, however, refer to the use of oil in this connection for simplicity in description.

The oil under pressure may be supplied from a central pumping plant, through suitable pipe lines to a plurality of wells, this fluid being forced downwardly through a pressure pipe to the bottom of the well, where it actuates a fluid motor, this motor being of the reciprocating type, and being utilized to actuate the pump plunger situated adjacent thereto. The pump draws oil from the well and delivers this oil with the exhaust from the fluid motor to the interior of the tubing, through which the pumped oil and the exhaust oil from the fluid motor is delivered to the surface of the ground, and through suitable piping to storage.

Further objects and advantages will be set forth more in detail hereinafter.

Referring to the drawing, which is for illustrative purposes only:

Fig. 1 is a diagrammatic view partly in section of a pump embodying my invention applied to an oil well.

- Fig. 2 is a section through the upper end of the fluid motor, showing the method of connecting the pressure pipe. 55
- Fig. 3 is a section on a plane indicated by the line 3—3 of Fig. 2. 56
- Fig. 4 is a section on a plane indicated by the line 4—4 of Fig. 2. 57
- Fig. 5 is a section through the upper part of the fluid motor showing the piston valve. 58
- 10 Fig. 6 is a section on a plane represented by the line 6—6 of Fig. 5. 59
- Fig. 7 is a section on a plane represented by the line 7—7 of Fig. 5. 60
- 15 Fig. 8 is a section on a plane represented by the lines 8—8 of Fig. 5. 61
- Fig. 9 is a section on a plane represented by the line 9—9 of Fig. 5. 62
- Fig. 10 is a section on a plane represented by the line 10—10 of Fig. 5. 63
- 20 Fig. 11 is a section on a plane represented by the line 11—11 of Fig. 5. 64
- Fig. 12 is a section of the same portion of the pump as shown in Fig. 5, but taken at right angles thereto. 65
- 25 Fig. 13 is a section on a plane represented by the line 13—13 of Fig. 12. 66
- Fig. 14 is a section on a plane represented by the line 14—14 of Fig. 12. 67
- 30 Fig. 15 is a section on a plane represented by the line 15—15 of Fig. 12. 68
- Fig. 16 is a section joined directly to the section shown in Fig. 5, showing further details of the fluid motor. 69
- 35 Fig. 17 is a view of the same apparatus on a section at right angles to Fig. 16. 70
- Fig. 18 is a sectional view of the deep well pump. 71
- 40 It should be understood that Figs. 2, 5, 16 and 18 form a single series when joined together in the order named from top to bottom, as do also Figs. 12 and 17. 72
- 45 The method of installing my invention in a well is illustrated in Fig. 1, in which 21 is a derrick, and 22 is the casing of the oil well, this casing extending down into the oil sands 23. Suspended on a string of tubing 24 is a fluid motor 25 and a deep well pump 26. The tubing 24 extends upwardly through the well, being supported 73
- 50 in a casing head 27 and being connected through a pipe 28 with suitable storage. A pressure pipe 30 extends downwardly through the tubing 24, being suspended inside the tubing, a stuffing box 31, being provided at the top of the well between the pressure pipe 30 and the tubing 24. The pressure pipe 30 is connected through a pipe 32 with a pressure pump 33, which may be 74
- 55 driven by steam or by a gas engine, or by an electrical motor. The pressure pump 33 may be placed in, or close to the derrick 21, or it may be located at some central point and utilized to pump a number of wells. The pressure from the pump 33 is used to 75

actuate the fluid motor, which in turn actuates the deep well pump 26. 85

The exact details of construction of the motor 25 and pump 26 will be understood from the following description. 90

Secured on the lower end of the tubing 24 by means of a collar 35 is an anchor head 36, this anchor head having an exhaust passage 37 therethrough, and having a conical opening in which a conical plug 38 is adapted to seat in fluid-tight relationship. The plug 38 is secured to the end of the pressure string 30 by means of a collar 39. A bleeder opening 40 is provided in the anchor head, this opening being closed by the plug 38 when the pressure pipe 30 is in place, but being open whenever the pressure pipe is pulled upwardly so that the plug 38 is lifted. 95

In installing the apparatus in the well, the tubing is first put in place and secured in the casing head 27, and the pressure pipe 30 is then installed, being lowered into the tubing, joint by joint, until the plug 38 seats in the conical head 36, the ordinary lifting apparatus in the derrick 21 being utilized to install and remove both the tubing 24 and the pressure pipe 30. 85

The object of the bleeder opening 40 is to allow the tubing 24 to be drained whenever the pressure pipe 30 is withdrawn, so that in raising the tubing and pump for repairs it is unnecessary to also raise the oil in the tubing. It should be understood that if the tubing is pulled from the well when full of oil, that each joint as disconnected at the surface of the ground will discharge the oil, thus making what is known as a wet job. The bleeder opening 40 prevents this, as the tubing readily drains as it is withdrawn. 95

With the pressure pipe 30 in place, oil pressure is delivered through a screen 50 into a pressure pipe 51, which extends down and is secured in a member 52 forming a part of the casing 53, which is secured by means of a collar 54 to the anchor head 36. The member 52 is secured by a collar 55 to an upper stuffing box barrel 60. The upper stuffing box barrel 60 is secured by means of a collar 61 to a piston valve barrel 62, which is secured by means of a collar 63 to a lower stuffing box barrel 64. The lower stuffing box barrel 64 is connected by a collar 65 with a motor barrel 66, the lower end of this barrel being threaded in a packer section 67, which in turn is threaded on a pump barrel 68. The pump barrel 68 is threaded in a collar 69, which carries a nipple 70 in which a standing valve seat 71 is secured. 100

Sliding in the piston valve barrel is a piston valve 80 which is slidably mounted on a sleeve 77, the sleeve being held between collars 79 for the purpose of forming a fluid tight chamber in the barrel. Extending 115

through the piston valve barrel is an upper tube 81 which extends down and is secured to a motor plunger 82 sliding in the motor barrel 66. The motor plunger 82 is also provided with a lower tube 83, which extends downwardly and connects into a working valve seat 84, carried on the top of a pump plunger 85, which slides in the pump barrel 68. The tubes 83 and 81 are hollow and are in open communication with each other through an opening in the motor plunger 82, so that fluid which passes through the working valve seat 84 of the plunger 85 has an open passage upwardly through the tubes 83 and 81 and the motor plunger 82 into the interior of the member 53, and, from the member 53 through the exhaust passage 37 into the space inside the tubing 24, and outside the pressure pipe 30. The pump operates in the usual manner, the plunger 85 being raised and lowered by the tube 83, thus lifting the oil through a standing valve 90, having a ball valve 91 therein, by means of the working valve 84 and an auxiliary working valve 92. On the down stroke, balls 93 and 94 are lifted, the oil flowing upwardly past these balls and upwardly through the members 83, 82 and 81 into the interior of the member 53. The operation of the pump is exactly similar to the ordinary pump in so far as raising oil through the tubing 24 is concerned. The pump is, however, actuated by the fluid motor 25 which in turn is actuated by the fluid under pressure delivered through the pressure pipe 30. This fluid under pressure is delivered through the pipe 51 to a pressure passage 100, which extends downwardly through the members 60, 62 and 64, and which is provided with ports 101, 102 and 103. The interior of the member 53 is also connected to an exhaust passage 105 which extends downwardly through the members 60 and 62, and which is provided with ports 106 and 107. Packing 110 is provided around the tube 81 inside the member 60 and around the tube 81 inside the member 64. Packing is also provided around the tube 83 inside the member 67. The motor plunger 82 is supplied with pressure through two passages, namely, a passage 115 which communicates with the bottom of the motor barrel 66, and a port 116 which communicates with the top of the motor barrel 66. The passage 115 extends upwardly through the members 66, 64 and 62, and is provided at its upper end with ports 117 and 118. The passage 116 extends upwardly through the members 64 and 62 and is provided with ports 119 and 120. The application of pressure to the plunger 82 through the passage 115 raises the plungers 82 and 85, and the application of pressure through the passage 116 forces these plungers downwardly.

This pressure is applied to either passage by means of the piston valve 80. With the piston valve in its lower position, fluid under pressure is taken from the passage 100 through the port 102, and is delivered through the port 118 to the passage 115. The fluid so delivered passes into the motor barrel 66 below the plunger 82, lifting same, and at the same time the exhaust fluid from above the motor plunger 82 passes upwardly through the passage 116 and through the ports 120 and 107 and upwardly through the exhaust 105 into the interior of the member 53.

The plungers 82 and 85 are forced downwardly whenever the piston valve 80 is in its extreme upper position. In this position pressure is taken through the port 102 from the passage 100 and is delivered through the port 119 into the passage 116. This applies pressure to the top of the plunger 82, the exhaust from below this plunger passing upwardly through the passage 115 and being delivered through the ports 117 and 106 to the exhaust passage 105. In other words, when the piston valve is in its lower position, pressure is applied to the plungers to lift them, and when the piston valve 80 is in its upper position, pressure is applied to the plungers to force them downwardly.

The piston valve 80 is itself operated by fluid pressure in the following manner:

Formed in the tube 81 as shown in Fig. 2, is a longitudinal channel 130 communicating with grooves 131 and 132. Similarly on the lower end of the tube 81 there is a longitudinal channel 140 having grooves 141 and 142 as shown in Fig. 16. Opening through the tube 81 between the grooves 141 and 131 are openings 150 as shown in Fig. 12. The tube 81 is rigidly connected to the motor plunger 82 and moves therewith. As the motor plunger approaches its upper position, the grooves 141 and 142 register with the port 103 in the pressure passage 100 and with a port 145 shown in Fig. 16 in a passage 146, which communicates with the bottom of the plunger valve barrel below the piston valve 80, as shown in Fig. 5. Pressure is therefore exerted to lift the piston valve 80. The upper end of the piston valve barrel communicates as shown in Fig. 12 through a port 161 with a passage 160, having ports 162 and 163. At the same time that the groove 141 registers with the port 103, as just described the openings 150 register with the port 162, thus providing an open communication from the top of the plunger valve barrel above the piston valve 80 through the port 161, the passage 160, the port 162 and the hole 150, with the interior of the pipe 81. This allows the fluid to flow from above the piston valve, into the interior of the tube 81 and the piston valve 130.

can move upwardly. When the plungers 82 and 85 approach the lower end of their stroke, the grooves 131 and 132 come into action, the groove 131 registering with the 5 port 163 and the groove 132 registering with the port 101. This allows fluid under pressure from the pressure passage 100 to flow through the port 101 through the groove 130 and through the port 162 into the passage 160, and from this passage through the port 161 into the space above the piston valve 80. This tends to force the piston valve downwardly.

15 The method of operation is therefore as follows:

With the parts in the position shown in the drawing, the motor piston 82 is being forced upwardly, lifting the oil by means of the pump plunger 85. As soon as the ports 20 141 and 142 register properly with the ports 103 and 145, which will be at or near the extreme top of the plunger stroke, pressure is applied to the bottom of the piston valve 80 as has previously been explained, and the 25 piston valve is lifted, the fluid from above the piston valve 80 being exhausted through the openings 150 as previously described. The piston valve 80 is therefore moved upwardly and the connection of the fluid pressure to the motor piston 82 is reversed, so that pressure is delivered to the motor piston tending to force it downwardly. When the motor piston reaches the bottom of its stroke, the grooves 131 and 132 come into 30 play, pressure being applied to the top of the piston valve 80 to force it downwardly.

Summing the whole operation up, it will be seen that the movement of the plunger 82 is controlled by the piston valve 80, the 40 plunger moving upwardly when the piston valve is down, and downwardly when the piston valve is up. The piston valve is shifted from its up to its down position by the grooves 131 and 132, and the grooves 45 141 and 142 acting in conjunction with the holes 150. It may be explained that the hole 150 is so situated that when the plungers are in their extreme lower position, it communicates with the port 260 connecting 50 to the passage 146, thus placing the lower end of the piston valve barrel in open communication with the interior of the tube 81 through the passage 146, the port 160 and the holes 150. It will be seen that the pressure delivered through the pressure pipe 30 is thus utilized to reciprocate the plungers 82 and 85, and to shift the piston valve 80 up and down at the end of the plunger stroke to reverse the direction of the application of 55 the fluid pressure to the plunger.

60 By the use of my invention, it is possible to entirely dispense with the ordinary sucker rods, and it is further possible to pump a large number of wells by simply piping fluid 65 under pressure from a central pressure

pump system to the individual wells. By the use of my invention the wear and tear of the pump rods is done away with and the great expense due to breakage of the pump rods is also done away with. It is 70 further possible to operate my pump at a much higher number of strokes than is possible through sucker rods, so that larger quantities of oil may be pumped from the well than has heretofore been considered 75 possible.

While I have shown and described my invention as applied to an oil well pump, it should be understood that this invention is applicable to all sorts of pumps. It is further to be understood that in some cases, it is preferable to use compressed air as a motive power, this air flowing downwardly through the pressure pipe 30, actuating the fluid motor 25 and then being mixed with 85 the upwardly flowing stream of oil, so that its lifting power can be utilized therein. While I have shown and described a preferred embodiment of my invention, it should be distinctly understood that this is 90 for illustrative purposes only, the scope of my invention being limited by the annexed claims.

I claim as my invention:

1. In pumping equipment, the combination of: tubing arranged to extend within a well; pump mechanism secured to the lower end of said tubing; a fluid motor adapted to be operated in all phases of motion by fluid under pressure, said motor being associated with said pump mechanism; a fluid pressure pipe extending downwardly within said tubing; and means for delivering the discharge of said pump mechanism into the space between said tubing and said pressure pipe wherein said discharge is conducted to the ground surface. 95

2. In pumping equipment, the combination of: tubing arranged to extend within a well; pump mechanism secured to the lower end of said tubing; a fluid motor adapted to be operated in all phases of motion by fluid under pressure, said motor being associated with said pump mechanism; a fluid pressure pipe extending downwardly 100 within said tubing; and means for delivering the discharge of said pump mechanism and the exhaust of said motor into the space between said tubing and said pressure pipe wherein said discharge and said exhaust are 105 conducted to the ground surface. 115

3. In pumping equipment, the combination of: tubing arranged to extend within a well; pump mechanism secured to the lower end of said tubing; a fluid motor adapted to be operated in all phases of motion by fluid under pressure, said motor being associated with said pump mechanism; a fluid pressure pipe extending downwardly 120 within said tubing; a fluid actuated valve for 125

- said fluid motor; valve means actuated in consequence of the piston of said fluid motor reaching its extreme positions for controlling the flow of fluid for actuating said 5 valve for said motor; and means for delivering the discharge of said pump mechanism into the space between said tubing and said pressure pipe wherein said discharge is conducted to the ground surface.
- 10 4. In pumping equipment, the combination of: tubing arranged to extend within a well; pump mechanism secured to the lower end of said tubing; a fluid motor associated with said pump mechanism; a fluid pressure pipe extending downwardly within said tubing; a piston valve for said fluid motor, said piston valve having an up and a down position whereby fluid from said pressure pipe is delivered to propel the piston of said 15 fluid motor upwardly and downwardly; valve means functioning, when said piston of said motor is in extreme positions, to deliver fluid under pressure for moving said piston valve between up and down positions; 20 and means for delivering the discharge of said pump mechanism into the space between said tubing and said pressure pipe wherein said discharge is conducted to the ground surface.
- 25 5. In pumping equipment, the combination of: tubing arranged to extend within a well; pump mechanism secured to the lower end of said tubing; a fluid motor associated with said pump mechanism; a fluid pressure pipe extending downwardly within said tubing; a fluid actuated valve for said fluid motor; and valve means actuated in consequence of the piston of said fluid motor reaching its extreme positions for 30 controlling the flow of fluid for actuating said valve for said motor.
- 35 6. In pumping equipment, the combination of: tubing arranged to extend within a well; pump mechanism secured to the lower end of said tubing; a fluid motor associated with said pump mechanism; a fluid pressure pipe extending downwardly within said tubing; a piston valve for said fluid motor, said piston valve having an up and a down position whereby fluid from said pressure pipe is delivered to propel the piston of said fluid motor upwardly and downwardly; and valve means functioning, when said piston of said motor is in extreme positions, to deliver fluid under pressure for moving said piston valve between up and down positions.
- 40 7. In pumping equipment, the combination of: tubing arranged to extend within a well; pump mechanism secured to the lower end of said tubing; a fluid motor associated with said pump mechanism; a fluid pressure pipe extending downwardly from the ground surface to said fluid motor; means for delivering fluid under pressure to said pressure pipe; a fluid actuated valve for said fluid motor; and valve means actuated in consequence of the piston of said fluid motor reaching its extreme positions for controlling the flow of fluid for actuating said valve for said motor.
- 45 8. In pumping equipment, the combination of: tubing arranged to extend within a well; pump mechanism secured to the lower end of said tubing; a fluid motor associated with said pump mechanism; a fluid pressure pipe extending downwardly from the ground surface to said fluid motor; means for delivering fluid under pressure to said pressure pipe; a piston valve for said fluid motor, said piston valve having an up and a down position whereby fluid from said pressure pipe is delivered to propel the piston of said fluid motor upwardly and downwardly; and valve means functioning, when said piston of said motor is in extreme positions, to deliver fluid under pressure for moving said piston valve between up and down positions.
- 50 9. In pumping equipment, the combination of: a cylinder of tubular characteristics; a piston operable in said cylinder; a hollow rod extending through and secured to said piston; a valve barrel adjacent to and in alignment with said cylinder, said hollow rod extending through said valve barrel; and a piston valve in said valve barrel, said piston valve being slidably mounted on said hollow rod and being arranged to control the flow of fluid for motivating said piston, said hollow rod having channels formed therein for permitting a flow of fluid to the opposite ends of said piston valve when said piston reaches its extreme positions.
- 55 10. In pumping equipment, the combination of: a cylinder of tubular characteristics; a piston operable in said cylinder; a hollow rod extending through and secured to said piston; a valve barrel adjacent to and in alignment with said cylinder, said hollow rod extending through said valve barrel; a piston valve in said valve barrel, said piston valve being slidably mounted on said hollow rod and being arranged to control the flow of fluid for motivating said piston, said hollow rod having channels formed therein for permitting a flow of fluid to the opposite ends of said piston valve when said piston reaches its extreme positions; and pump structure at the end of said hollow rod opposite to said piston valve, arranged to deliver liquid through said hollow rod.
- 60 11. In testimony whereof, I have hereunto set my hand at Los Angeles, California, this 9th day of August, 1928.
- ROLAND R. CRUM.
